UNITED STATES PATENT OFFICE.

FREDERICK SCHILLING, SR., OF SEATTLE, WASHINGTON.

FOLDING TENT.

1,345,108.

Specification of Letters Patent. Patented June 29, 1920.

Application filed April 28, 1919. Serial No. 293,139.

To all whom it may concern:

Be it known that I, FREDERICK SCHILLING, Sr., a citizen of the United States, and resident of Seattle, King county, Washington, 5 have invented certain new and useful Improvements in Folding Tents, of which the following is a specification.

My invention relates to tents and consists of a novel frame structure and the cover 10 which fits thereon.

The object of my invention is to provide a tent frame structure which may be collapsed and which is composed of small members so that when collapsed it will make a small 15 bundle. Also to provide such a collapsible tent frame structure which may be quickly and easily taken apart and put together, and which when put together will be of strong construction, and also one which will provide 20 a support for a web which may be used as a cot or bed supporting surface.

In the accompanying drawings I have shown my invention by a number of views 25 illustrative of the details of construction which I now prefer as being best adapted for this purpose.

Figure 1 shows in perspective a tent in erected condition in which my invention has been employed.

30 Fig. 2 shows in perspective the tent frame or supporting structure.

Fig. 3 is an end elevation of a tent employing my collapsible supporting frame in erected position.

35 Fig. 4 is a side view of the longitudinal bars which support the cot and their relationship with the ground sills.

Fig. 5 shows in perspective the construction of the ends of the parts which form the 40 side rail, and to which one side of the bed fabric or cot is secured.

Fig. 6 shows in perspective the various elements which form one of the end frame structures and the parts which connect 45 therewith, the various parts being in some cases shown as slightly separated.

Fig. 7 shows the manner of constructing the pivot between two members.

In the device which is the subject of this 50 invention all of the parts of the frame structure are made of comparatively short lengths and these are pivoted together so as to fold, or are secured together by a type of pin and socket construction which enables 55 them to be securely connected together and easily disconnected when desired.

As the base for the tent frame structure I employ a set of ground sills 1. These sills are made of boards which are fairly wide and are cut down at their upper edge 60 throughout the central portion thereof, to form a depression or wide notch 10. To each end is pivoted a post 2. The pivot connection of these posts is at the point 20 which is close to the bottom edge of the 65 ground sill 1, and close to the lower end of the post 2. The post 2 which is pivoted to one end of the ground sill is at the opposite side of said sill from the post which is pivoted to its opposite end, whereby these two 70 posts may fold down against the side of the ground sill and the two posts lie respectively at opposite sides of the sill.

The longitudinally extending bars 3, 75 which form the side bars of the cot structure, are also made in a plurality of sections which are hinged together. These are shown in side elevation in Fig. 4. The various sections 3 are connected at their adjacent ends by means of hinges 30. These 80 hinges are preferably of the type of construction shown in Fig. 5. This consists of two plates 31 which are secured to the top surface of the respective bars 3 and are connected by a loop 32. This forms a flexible 85 hinge which will permit a slight side movement of the bars 3 with respect to each other.

When the bars 3 are put in position in the tent frame, their ends are intended to abut 90 together.

Means are provided whereby these side bars 3 may be securely held and supported by the ends of the ground sills 1. Means are also provided whereby the side bars 3 95 serve to accurately space and securely hold the sills 1 at the proper distance from each other and also to assist in holding these in vertical position, that is, prevent them rocking sidewise.

Such means as herein shown, consists of bracket arms 33 which are secured to the ends of the sections 3 at such a distance from their meeting ends as will cause the edges of the bracket arms to engage snugly 100 with the side surfaces of the ground sills 1 when the parts are in position. In addition the upper edges of the ground sills 1 are provided with slots, as 11, of such width and depth as to receive the bars 3. In this 110 manner the bars 3 are well supported against movement transversely of their length, and

by reason of the bracket arms 33 they are held against movement in the direction of their length. The two bars 3 which are placed at opposite sides of the tent, form side bars of a cot, as they have a canvas 34 secured thereto. The notching downward of the ground sills in the center to form the large depression or notch 10, prevents the body of the occupant of the tent from resting upon these sills.

The notches 11 in the sills are so placed with relation to the position and size of the post 2, that their outer edges coincide in position with the inner edges of the post 2, when the latter are raised. This is clearly shown in Figs. 3 and 6. In consequence the bars 3 form supports to retain the post 2 in raised position, at least so far as preventing inward movement. The posts are connected together to prevent outer movement, both by other members of the frame structure and also by the canvas cover which is provided.

The type of joint which is used for connecting the various sections of the tent frame, is illustrated in detail in Fig. 6. Surrounding the end of one section of the post is a clip 5, which has one side spaced away from the face of the post a short distance, as is shown at the point 50. This forms a socket for the reception of the tongue carried by the end of the other frame member which is to be joined at this point. The clip or band 51 which is secured upon the other frame member has a tongue 52 extending from one edge thereof and spaced away from a surface of the frame member a sufficient distance to permit the passage of the portion of the clip 5 which forms the outer wall of the socket 50 into this space. The tongue 52 may, therefore, be placed in the socket 50 and the two parts will then be held securely together and accurately positioned.

The exact shape of the tongue, together with its location and the location of the complementary socket 50, will depend upon the relationship between the parts to be connected. The manner of connecting the longitudinal bars 6 and 8 which support the sloping roof of the tent, is also illustrated in Fig. 6. Each of these bars, considered in its entirety, consists of three sections which are pivoted together as shown at 60, so that when disconnected from the other parts they may be folded into compact shape. The clip 53 which is placed at the end of these sections, is provided with a tongue 54 which enters the socket 50 formed by a clip 5. The clip 5 which is placed upon the upper end of the post section 21 at each of the corners of the tent, is provided with two socket members at opposite sides, one designed to receive the tongue 52 carried by the inclined brace member 7, and the other

to receive the tongue 54 carried by the outer end of one of the bars 6.

At the upper end of the inclined brace member 7, which occupies the relative position of a rafter in a house, the tongue 52 is bent backward at an acute angle, while the corresponding tongue 52 at the lower end of this bar, is bent in an obtuse angle. The principle of construction is, however, the same in each case.

As the inclined bar 7 would be longer than the horizontal bars which extend across the frame, it has been made in two sections which are pivoted together as at 70. In such cases as this, I prefer to provide the hinged joints with clamping bolts as 22, these clamping bolts being provided with thumb nuts, so that they may be tightly turned down without the use of a wrench.

The extreme upper bar of the frame which forms the peak of the tent, is also composed of three bar sections 8, pivoted together as at 80, so that they may fold when the tent is collapsed. The end sections 8 are each provided with a tongue, such as the tongue 54 shown in Fig. 6, which enters the socket 50 carried by the upper post section 21. The central portion of these bars 8 is additionally supported by a brace bar 81 which has its lower end secured to the post 21 by means of a clip, as 83, and a tongue carried by the bar 81, after the manner shown in Fig. 6. At its upper end this brace bar is pivoted at 82 to one of the bars 8.

The above type of structure is one which may be quickly and readily put up or taken down, and when taken down and disconnected may be folded into compact shape. It thus makes a bundle which may be conveniently transported, as for instance by parties who are traveling in automobiles, and may be quickly raised whenever desired. The provision of an elevated web, as 34, which may be used as a cot to sleep upon, avoids the danger and disagreeable effects of sleeping upon the ground. It also furnishes a more comfortable surface upon which to sleep.

The cover for this frame structure is composed of canvas and is stretched together so as to fit closely to the back and end sides and to the sloping roof portion. The end sides are provided with extensions 90 which are of such a width and length as to be capable of closing at least half of the front side of the tent when folded against the same. Preferably they are made sufficiently long as to have a reasonable amount of overlap when the two are folded together. They will also be provided along their upper edges with means for securing them to the tent frame, as for instance, eyelets or clasp buttons located as at 91. In addition to this I also provide an extension 92 from the inclined roof portion of the tent, of such

a width that it will fold well down against the face of the tent. The width of this member is one which will bring it down to approximately, if not entirely, to the ground. This extension 92 may be supported so as to form a roof section in front of the tent proper. The flaps 90 may also be carried out in the position corresponding with the position of the end sections 9 of the tent. In this case a large open fronted porch is formed in front of the sloping section. When both the flaps 90 and 92 are closed down, the tent becomes very tight and it would be difficult for the wind to enter. To further secure the tightness in the closure of the tent, and also to prevent the entrance of insects, I may provide narrow flaps, as 93, secured to the back side 94, and capable of being laid on top of the fabric which forms the cot surface.

It is believed that the manner of handling the parts in erecting and also in collapsing will be evident upon inspection. When collapsed the length of the bundle required is the length of the individual sections as 2—21 and 1. These members need not be of any large size, and if made of a light and strong wood will weigh but little. In consequence it is possible to carry in an automobile one or more of these tents and to thus furnish comfortable sleeping apartments for all the occupants of the vehicle.

What I claim as my invention is:

1. A tent frame comprising ground sills, posts pivoted at the ends of said sills to swing down along opposite sides of the sills, and longitudinal bars having interlocking engagement with the sills just within the posts and serving as a side support for said longitudinal bars.

2. A tent frame comprising ground sills, posts pivoted to the ends of said sills at opposite sides and adapted to swing down alongside said sills, the ends of the sills being transversely notched on their upper edge just within the raised position of the posts, side bars adapted to fit into said notches and to support the posts by engagement with their inner edges, and a fabric secured to and drawn taut between said side bars.

3. A tent frame comprising ground sills, posts pivoted to the ends of said sills at

opposite sides and adapted to swing down alongside said sills, the ends of the sills 55 being transversely notched on their upper edge just within the raised position of the posts, side bars adapted to fit into said notches and to support the posts by engagement with their inner edges, a fabric secured 60 to and drawn taut between said side bars, and brackets secured to the side bars and extending down along the sides of the sills, and acting to prevent rocking of said sills.

4. A tent frame comprising ground sills, 65 posts pivoted to the ends of said sills at opposite sides and adapted to swing down alongside said sills, the ends of the sills being transversely notched on their upper edge just within the raised position of the 70 posts, side bars composed of sections of a length to extend between adjacent sills, hinges connecting said sections, said side bars fitting within the notches in the upper edges of the sills, means carried by the side 75 bars to position the joints between sections over cross sills, and a fabric secured to said side bars.

5. A collapsible tent frame comprising ground sills, posts pivoted to the ground 80 sills and side bars having interlocking engagement with the ground sills and posts to hold them raised.

6. A collapsible tent frame comprising ground sills, posts pivoted to said sills to 85 fold alongside thereof, bars extending across and engaging said sills and one side of the posts when raised, sectional folding roof bars provided, together with the posts, with complementary pin-and-socket engaging 90 members.

7. A collapsible tent frame comprising ground sills cut down in their central portion and having transverse notches in their upper edges just inward from their ends 95 longitudinal side bars composed of sections of a length to reach from one ground sill to the next, and hinged together, and of a size to fit in the notches in the ground sills, and brackets secured to said side bars close 100 to their ends and adapted to engage the side faces of the ground sills to prevent their rocking over.

Signed at Seattle, Washington, this 18th day of April, 1919.

FREDERICK SCHILLING, Sr.
